UNITED STATES PATENT OFFICE.

LEMUEL COBURN, OF HOLYOKE, MASSACHUSETTS, ASSIGNOR TO THE COBURN TROLLEY TRACK MANUFACTURING COMPANY, OF SAME PLACE.

TROLLEY-SUPPORT FOR DOORS.

SPECIFICATION forming part of Letters Patent No. 447,505, dated March 3, 1891.
Application filed July 15, 1889; Serial No. 317,584. (Model.)

To all whom it may concern:

Be it known that I, LEMUEL COBURN, a citizen of the United States, residing at Holyoke, in the county of Hampden and State of Massachusetts, have invented new and useful Improvements in Trolley-Supports for Doors, of which the following is a specification.

This invention relates to trolley-supports for doors, which doors are capable of moving longitudinally along or within a partition or other wall, the principal object of the invention being to provide means for the suspension or support of the trolley-track, from which through suitable roller-carriers and hangers the door is supported, which means are simple and efficient with respect to the secure support of said trolley-track, and also permit of adjustment of the track to level it; and the invention consists in the construction and combination of parts, all substantially as will hereinafter more fully appear, and be set forth in the claims.

Reference is to be had to the accompanying drawings, in which this invention is illustrated, and in connection with which the following description is given, in which similar characters of reference indicate corresponding parts in all the views.

Figure 1 is a side elevation of a portion of a wall with a doorway and a door therefor supported from and movable on a trolley-track. Fig. 2 is an enlarged view of a part of the casing or heading above the doorway, the upper portion of a door, a section of trolley-track and the supporting and adjusting means therefor, and the roller-carriers and hangers for the suspension of the said door from the track, some of said parts being in elevation, while others thereof are shown in vertical longitudinal section. Fig. 3 is a vertical cross-sectional view of some of the parts shown in the preceding view, taken on the line 3 3. Figs. 4 and 5 are perspective views of parts employed for the support of the trolley-track, and Fig. 6 is a perspective view of one of the hangers.

In the drawings, A represents a partition-wall, having the doorway B therein, of which a is the upper casing or heading at which, and also extended beyond to one side thereof to an extent equal to the desired slide of the

door to be supported therefrom, is a trolley-track C. The said trolley-track may be secured on the under side of the heading, in which case the door would slide between the walls of the partition; or said track may be secured in a vertical plane parallel with but somewhat removed from the plane of the doorway, in which latter case the door would slide closely along but outside of the partition. Said trolley-track C consists of a tube, generally of a rectangular cross-sectional form at its upper portion and having its lower edges turned in toward the median line and then turned upward, so that the bottom of the tube has the trough-shaped ways b b at either side of the intermediate longitudinal opening c. The said trolley-track has devices for its support and is supported thereon, as will be now described.

D represents a bracket-casting of step form, by the upper horizontal portion e of which it is secured to the heading, and when so secured the other horizontal portion d stands horizontally and parallel to said portion e and somewhat below the heading. One end portion of the trolley-track has a screw f passing vertically through its upper wall and extended into the space within the said trolley-track some distance—a greater or less, as required—below the said upper wall of the said track, check-nuts g g being provided to effectually maintain said screw in adjustment, and the trolley-track by its end so provided, as just stated, is at its end passed by its longitudinal opening over and about the said lowermost step d of the bracket D, the lower end of the screw resting on said step, whereby the one end of the trolley-track is supported. The said trolley-track at or toward its other end portion is perforated through its upper wall, through which perforation is upwardly passed a screw h up to its head, said head being larger than said perforation and serving to support thereon the said end portion of the track, and said screw enters with a screw-engagement the under side of the heading; or, more precisely speaking and as practiced, the screw enters a screw-threaded bore i in a metallic plate j, that is secured on the under side of the heading a, and said plate is provided with check-pieces k k, sufficiently sepa-

rated to accommodate the width of the trolley-track between them and to serve as guards to prevent lateral movement of the end of the track adjacent thereto. The bracket-step *d* at the other end is of such a width as to closely fit between the side walls of the track, and thereby that end is also held against lateral movement. The said screw *h* is turned to enter within the bore of the said metallic plate until the trolley-track has been leveled.

It will be apparent from the construction described that the trolley-track may be maintained at a greater or less proximity to the heading, as required, and its position may readily be readjusted from time to time, as may become advantageous.

Each of the roller-carriers *E* employed in the present trolley contrivance consists of a pair of rollers separated corresponding with the separation of the troughways *b*, and a uniting axle, said carriers being adapted to freely roll backward and forward in said ways.

Each of the hangers consists of a horizontal bar *l* disposed within and longitudinally of the trolley-track and to lie on the axle of the roller-carrier for its support thereby, and pending posts *m m*, to the feet or lower portions of which the door, by its upper edge, is secured. Said posts *m* between the bar *l* and the top of the door are to be of such slight width as to freely pass through the longitudinal opening between the ways of the trolley-track. In practice two hangers and a roller-carrier for the support of each hanger is provided; but, if desired, one hanger having its longitudinal bar about equal to the width of the door with two roller-carriers therefor may be employed with fair results.

A door supported, as described, from a trolley-track may be readily slid alongside of a

wall or within such wall when it is made hollow, and, in conjunction with the adjusting devices for the trolley-track, the trolley form of suspension for doors becomes most readily adaptable for use in houses where the nearest approach to perfection in point of easy and true running of the doors is considered necessary.

What I claim as my invention is—

1. A wall or support having secured thereon a bracket-piece comprising, essentially, a longitudinal lug or extension *d*, combined with a tubular trolley-track, substantially as described, having in the upper wall of its one end portion the screw *f*, adapted to be turned inwardly and outwardly through said upper wall and resting by its lower end on said extension *d*, and a supporting-stud at and for the other end of the tubular track and having a screw engagement for a vertical adjustment upon the wall or support, substantially as described.

2. The combination, with a bracket-step *d* and a plate *j*, having a screw-bore and provided with cheek-pieces *k k*, of the tubular trolley-track, substantially as described, provided at one end portion with a screw passing with an engagement through its upper wall and adapted to be turned inwardly and outwardly through said upper wall and to rest by its lower end on said bracket-step, and provided at its other end portion with a supporting-screw which passes upwardly through said track and with a screw engagement into said bored plate, substantially as and for the purpose described.

LEMUEL COBURN.
